UNITED STATES PATENT OFFICE.

CHARLES MILLER, OF AUBURN, NEW YORK.

DUMPING-WAGON.

SPECIFICATION forming part of Letters Patent No. 286,052, dated October 2, 1883.
Application filed July 23, 1883. (No model.)

To all whom it may concern:

Be it known that I, CHARLES MILLER, a citizen of the United States, and a resident of Auburn, in the county of Cayuga and State of New York, have invented certain new and useful Improvements in Dumping-Wagons; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved dumping-wagon. Fig. 2 is a longitudinal vertical section of the same. Fig. 3 is a cross-section. Fig. 4 is a top view, and Fig. 5 is an end view.

Similar letters of reference indicate corresponding parts in all the figures.

My invention has relation to dumping-wagons, and it contemplates certain improvements upon the wagon for which Letters Patent No. 278,253 were granted to me on the 22d 25 day of May, 1883; and it consists, to that end, in the improved construction and combination of parts of the same, as hereinafter more fully described and claimed.

In the accompanying drawings, the letters A 30 A indicate the side pieces of the wagon, which may be mounted upon the running-gear in any suitable manner, and B a number of cross-bars passing transversely from the lower portions of the side pieces, and passing through two pairs 35 of longitudinal bars, C, between which a number of rollers, D, are journaled, upon which the flexible-slat bottom rests and rolls. This bottom consists of a number of transverse slats, E, fastened near their ends upon two endless 40 belts, F, which pass over two pairs of grooved wheels, G, secured upon two shafts, H, journaled in bearings at both ends of the wagon, in the lower portions of the side pieces, the said slat bottom extending the length of the side 45 pieces. Flat strips of sheet metal I are fastened upon the upper surfaces of the slats, overlapping the rear edges of the same, so as to prevent any small contents of the wagon from dropping through between the slats.

50 The upper edges of the side pieces are pro-

vided with laterally-extending flanges J, the edges of which are provided with downwardly-projecting flanges K, forming ways upon both sides of the upper edges, in which ways the upper ends of two sliding side pieces, formed 55 of slats L, fastened transversely upon two endless belts, M, slide, their lower ends bearing against the upper sides of the ends of the bottom slats when sliding inside the side pieces while the lower ends of the sliding slats slide 60 in ways N upon the outside of the side pieces when the sliding slats are drawn around the rear ends of the side pieces to slide upon the outside of the same, their upper ends sliding in the outer portion of the ways J K. The 65 endless belts pass over two rollers, O, pivoted vertically upon the rear ends of the side pieces, over which rollers the slats pass, and over two pairs of pulleys, P, journaled in the front ends of the side pieces.

The forward side slats are provided upon their insides with a pair of vertical cleats, Q, each, between which cleats the ends of the front end-gate, R, fit, the lower end of which is fastened to the foremost bottom slat, so that 75 when the bottom is drawn rearward the sliding side slats will also be drawn out, and to decrease the friction against the side pieces of the wagon-body a number of anti-friction rollers, S, are journaled in the said side pieces, 80 projecting with their rims outside the surfaces of the side pieces, so that the slats will roll upon them. To draw the sliding side slats forward after they have been drawn rearward, two belts, T, are fastened to the rearmost bottom 85 slat at one end and to the foremost side slats at the other end, passing over the forward shaft, H, and over a number of rollers, U, journaled upon the inner side of the lower ends of the side pieces.

The tail-gate V is suspended swinging from a transverse rod, W, fastened upon the upper edges of the side pieces, and the lower end of the same is held in place, prevented from swinging out by means of a lug or bolt, X, 95 projecting upward from the upper surface of one of the rearmost bottom slats, so that when the bottom is drawn out the gate will be allowed to swing out freely, allowing the load to be dumped.

A shaft, Y, having a crank, Z, upon its inner end, is journalled in bearings a upon the upper edge of one of the side pieces, within easy reach of the driver, and is provided upon 5 its outer end with a sprocket-wheel, b, over which a sprocket-chain, c, passes, which chain passes over a larger sprocket-wheel, d, journalled upon a shaft, e, projecting laterally upon the lower portion of the outside of the 10 side piece, near the front end of the same, and a pinion, f, is fastened upon the inner face of the said sprocket-wheel, and meshes with a larger pinion, g, fastened upon the outer end of the forward shaft. In this manner the 15 driver may remain in his seat, and by turning the crank at his side revolve the forward shaft, drawing the slat bottom and sides out, dumping the load, the sliding side slats avoiding the friction of the load upon the side pieces, 20 thus rendering the dumping of the load easier than where the load is simply discharged by a traveling slat bottom.

Having thus described my invention, I claim and desire to secure by Letters Patent of the 25 United States—

1. In a dumping-wagon, traveling side pieces composed of vertical slats traveling rearward, as and for the purpose shown and set forth.

2. In a dumping-wagon, traveling side pieces traveling rearward upon the inside of the stationary side pieces, passing around the rear ends of the same, and traveling forward upon the outside of the same, as and for the 35 purpose shown and set forth.

3. In a dumping-wagon, the traveling slat side pieces passing over rollers at the rear ends of the stationary side pieces, and fastened upon endless belts passing over the rollers at 40 the rear ends and over rollers at the front ends of the side pieces, as and for the purpose shown and set forth.

4. In a dumping-wagon, the combination of traveling slat sides, fastened upon endless belts 45 passing over vertical rollers at the rear ends of the stationary side pieces and over pulleys at the front ends of the side pieces, with a traveling slat bottom, and means for operating the same, as and for the purpose shown and set forth.

5. The combination of traveling slat side pieces passing rearward around the rear ends of the stationary side pieces and forward upon the outside of the same, a rearwardly-traveling slat bottom, and an end-gate fastened with 55 its side edges to the traveling side pieces and with its lower end to the traveling bottom, as and for the purpose shown and set forth.

6. The combination of the stationary side 60 pieces of a wagon, forming ways upon their upper edges extending to both sides, and ways upon their outsides in height with the bottom, and having vertical rollers at their rear ends and pulleys at their forward ends, sliding side

pieces composed of vertical slats sliding with 65 their ends in ways upon the side pieces, and fastened upon endless belts passing over the rollers at the ends of the same, a traveling slat bottom, and an end-gate fastened to the forward ends of the side pieces and the bottom, as and for the purpose shown and set forth. 70

7. A traveling slat bottom having metallic strips fastened upon the upper surfaces of the slats, overlapping the forward edges of the adjoining slats, as and for the purpose shown and set forth. 75

8. The combination of the traveling flexible bottom, having an upwardly-projecting lug upon its upper surface, near its rear end, 80 with a tail-gate swinging in a vertical plane at the rear end of a wagon, and impinging upon the traveling bottom of the same, as and for the purpose shown and set forth.

9. The combination of traveling flexible 85 side pieces sliding in ways upon both sides of the stationary side pieces, around their rear ends, a traveling flexible bottom, an end-gate fastened to the forward ends of the traveling sides and bottom, and belts fastened to the 90 rear end of the traveling bottom, passing over rollers, and fastened at their other ends to the front ends of the traveling sides, as and for the purpose shown and set forth.

10. The combination of the traveling flexible 95 sides and bottom, the latter passing over two transverse shafts in the ends of the wagon, the pinion fastened upon the forward shaft, the pinion and sprocket-wheel journalled near the front end of one of the side pieces, the 100 sprocket-chain, and the crank-shaft journalled upon the front end of the upper edge of the side piece, and having a crank upon its inner end and a sprocket-wheel upon its outer end, as and for the purpose shown and set forth. 105

11. The herein-described dumping-wagon, consisting of the side pieces having ways and anti-friction rollers, the vertical rollers at the rear ends, the pulleys at the front ends of the side pieces, the longitudinal roller-ways, the 110 sliding slat sides having endless belts, the traveling slat bottom having endless belts, the forward end-gate fastened to the traveling sides and bottom, the shafts having grooved wheels for the reception of the endless belts of the 115 bottom, the overlapping sheet-metal strips upon the bottom slats, the swinging tail-gate, and the means for operating the forward shaft, all constructed, combined, and arranged to operate as and for the purpose shown and set 120 forth.

In testimony that I claim the foregoing as my own I have hereunto affixed my signature in presence of two witnesses.

CHARLES MILLER.
